(57) **CLAIM**

The ornamental design for an indoor electrical outlet cover, as shown.

DESCRIPTION

FIG. 1 is a front perspective view of an indoor electrical outlet cover showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings are for the purpose of illustrating portions of the indoor electrical wall outlet cover that form no part of the claimed design. The dot-dash broken lines in FIGS. 2 and 5-8 are for the purpose of illustrating the boundary of the claim and form no part of the claimed design. The indoor electrical wall outlet cover is shown with symbolic breaks in length, and the appearance of any portion of the article between the break lines from no part of the claimed design.
